Sigal

[11] Patent Number: Des. 367,350

[45] Date of Patent: **Feb. 20, 1996

[54] **TOY BANK IN THE FORM OF A FOOTBALL HELMET**

Attorney, Agent, or Firm—Leonard Bloom

[76] Inventor: **Cindy S. Sigal**, 4002 Balmoral Rd.,
Baltimore, Md. 21208

[57] CLAIM

[**] Term: **14 Years**

The ornamental design for a toy bank in the form of a football helmet, as shown and described.

[21] Appl. No.: **30,661**

DESCRIPTION

[22] Filed: **Nov. 4, 1994**

FIG. 1 is a perspective view of a toy bank in the form of a football helmet, the broken lines forming no part of my design;

[52] U.S. Cl. **D99/37**

FIG. 2 is a top plan view thereof;

[58] Field of Search **D99/34, 35, 37,**

FIG. 3 is a bottom plan view thereof;

D99/38, 39; D6/557; D9/311, 317; D11/160,

FIG. 4 is a left side elevation thereof;

162; D21/150, 151, 160, 166; 232/1 D,

FIG. 5 is a right side elevation thereof;

5, 14, 15; 446/9, 10, 11, 12

FIG. 6 is a front view thereof;

FIG. 7 is a rear view thereof;

FIG. 8 is a section view, taken along the lines 8—8 of FIG. 1;

FIG. 9 is a further section view, corresponding to a portion of FIG. 8 and drawn to an enlarged scale, and showing the toy bank being molded of plastic (rather than wood in FIGS. 1—8); and,

FIG. 10 is a still further section view, corresponding to FIG. 9, but showing the use of metal.
